METHOD OF FOLDING PARACHUTES

Filed June 30, 1924

INVENTOR
Samuel Wiley
BY *W.H. French*
ATTORNEY

UNITED STATES PATENT OFFICE.

SAMUEL WILEY, OF METUCHEN, NEW JERSEY.

METHOD OF FOLDING PARACHUTES.

Application filed June 30, 1924. Serial No. 723,369.

(GRANTED UNDER THE ACT OF MARCH 3, 1883; 22 STAT. L. 625.)

To all whom it may concern:

Be it known that I, SAMUEL WILEY, a citizen of the United States, and a resident of Metuchen, county of Middlesex, and State of New Jersey, have invented an Improvement in Methods of Folding Parachutes, of which the following is a specification.

The invention described herein may be used by the Government, or any of its officers or employees in prosecution of work for the Government, or by any other person in the United States, without payment to me of any royalty thereon, in accordance with the act of March 3, 1883.

The subject of this invention is a method of folding parachutes.

When parachutes are folded for insertion in signal cartridges or in other containers, it is obvious that careful and delicate manipulation in packing is necessary in order to insure the opening of the parachute in a proper manner so that the suspension cords will not become entangled, thus preventing the proper functioning of the parachute.

The method now in vogue of folding parachutes consists in grasping the apex of the parachute, drawing and accordion plaiting the various segments, smoothing the folds into cylindrical form and then folding the entire parachute double. The suspension cords are coiled and placed against the side of the folded parachute and the bundle again folded over the cords. Another method consists in conveniently folding the parachute, rolling it into a cylindrical bundle and then wrapping the cords around the rolled bundle.

My improved method of folding a parachute is designed to afford better and more positive functioning by inverting the apical portion within the circumferential portion of the parachute so that when the parachute is expelled from the container it will be in a position to immediately distend. This method of folding a parachute also permits the suspension cords to be conveniently tucked under one of the outer folds for protection against entanglement and to insure immediate release to reduce the probability of the parachute being consumed due to sustained proximity of the ignited signal or illuminating composition suspended by the parachute.

To these and other ends, my invention consists in the arrangement, and combination of elements, described hereinafter and pointed out in the claims forming a part of this specification. 55

A practical embodiment of my invention is illustrated in the accompanying drawing, 60 in which,

Fig. 1 is a view of a distended parachute equipped with a chain of signal or illuminating members;

Fig. 2 represents the first step in folding the parachute;

Fig. 3 represents the second step in folding the parachute;

Fig. 4 represents the third step in folding the parachute; and

Fig. 5 shows the manner of disposing the suspended cords. 70

Referring to the drawings by numerals of reference:

The parachute comprises a circular envelope 10 which may be formed of a single piece of material or composed of a plurality of triangular segments 11 joined to each other to form a circumference 12 and meeting at an apex 13. Secured to each juncture 75 of the segments at their circumference are suspension cords 14 of equal lengths, their free ends knotted as at 15. Attachable to the knotted ends 15 is a signaling or illuminating device herein shown as a chain of 80 signals or illuminants 16.

In folding the parachute according to my method the parachute is distended as shown in Figure 1, so that the circumference and suspension cords are in functioning position. 90 The apical portion is then depressed or inverted to form a pocket as in Figure 2 and folded back on its own length as shown in Figure 3. The suspension cords attached to the circumference are then pulled down, 95 drawing the circumferential portion which has not been depressed over the folded portion as shown in Figure 4.

The suspension cords which are equally spaced about the circumference of the parachute are folded and tucked under one of the outer folds of the parachute which serves as a protection, only the knotted portions of the cords to which the signal or illuminating chain is attached protruding as shown in 105 Figure 5.

Upon discharge from a container, the parachute will immediately be distended allowing the suspension cords and their attached signal chain to fall free, thereby reducing the probability of the flame from the signal chain consuming the parachute. By this method of folding, I also obviate the necessity for plaiting the segments before folding.

While in the foregoing there has been illustrated and described such combination and arrangement of elements as constitute the preferred method of carrying out my invention, it is nevertheless desired to emphasize the fact that interpretation of the invention should only be conclusive when made in the light of the subjoined claims.

I claim:

1. The method of folding a parachute in-

cluding suspension cords consisting of depressing the apical portion, folding the apical portion upon itself, drawing the circumferential portion about the apical portion, and tucking the suspension cords under a fold of the circumferential portion.

2. The method of folding a parachute consisting of depressing the apical portion, folding the apical portion, and drawing the circumferential portion about the apical portion.

3. The method of folding a parachute consisting of depressing the apical portion, drawing the circumferential portion about the apical portion and then tucking the suspension cords within the circumferential portion.

SAMUEL WILEY.
